UNITED STATES PATENT OFFICE.

LOUIS R. CARBEIL, OF SAVANNA, ILLINOIS.

WRENCH.

Application filed September 18, 1926. Serial No. 136,218.

My invention has reference to wrenches, and aims to increase the efficiency of a similar device for which Letters Patent of the United States No. 1,464,004 were issued to 5 George W. Kelly August 7, 1923. The general arrangement and operation of the present tool is largely similar to that of said patented device, which was provided with a fixed jaw and a jaw movable with relation 10 thereto, and provided with a ratcheted control.

In said former invention the jaws were brought into closer position with relation to each other by placing the thumb or finger 15 of the operator against the movable jaw and forcing it in the direction of the fixed jaw. The jaws were then capable of being reopened by means of a slide-pin and button thereon, such slide-pin being connected with 20 an extension of the movable jaw, so as to assist in moving the same away from the fixed jaw. In some cases the head of the wrench was in such a limited space that it was difficult or impossible to insert the 25 thumb or finger for operating the same. The chief purpose of the present invention is to provide means whereby the movable jaw can be actuated in either direction by use of a slide-pin and parts associated therewith. A quick action of the jaws in either 30 opening or closing the same is thus secured, this operation being capable of being performed by either hand of the user, and on either side of the tool.

35 In the drawings:—

Fig. 1 is a side elevation of a wrench embodying the invention.

Fig. 2 is a similar view with the head of the wrench shown in section.

40 Fig. 3 is a detail of the jaw 10.

Fig. 4 is a detail of the pin 8 and appurtenant parts.

The invention comprises a head portion 1, projected into a fixed jaw 2 in one direction, and into a handle 3 in the opposite direction. Extending through said head is a recess 4, on opposite sides of which are plates 5 and 6, forming the main part of the head. Formed in said plates are slots 7, 45 in which is slidable a pin 8, with which is connected the tongue 9 of a movable jaw 10, one face of which is adapted to cooperate with the face of the jaw 2 to assist in holding an object between said jaws. The union 50 between the pin 8 and tongue 9 is a rigid

one, produced by pressing the pin into an opening in the tongue, although other methods of uniting said parts so that they will operate together may be employed. The inner end of the jaw 10 is provided with 60 serrations, as shown at 11, for engagement with similar teeth 12 on the edges of the plates 5 and 6. Said teeth are held yieldably in engagement by means of a spring 13 fixed at one end in one of the ends of the 65 recess 4, and bearing against the inner end of the tongue 9.

On each end of the pin 8 is a thumb-bottom 14, formed of a circular plate 15, having a raised portion on opposite sides 70 of which are recesses 16 and 17. By means of said thumb-buttons the pin 8 can be moved in either direction in the slot 7, carrying with it the movable jaw 10. The thumb-button shown in Fig. 1 of the drawings is more convenient for operation by the thumb of the right hand. In closing the jaws the thumb is placed on the button 14 so as to press against the shoulder formed by the edge of the recess 16, and in sliding 75 the pin upwardly in the slot there is an initial rocking movement of the pin tending to disengage the teeth 11 and 12. The jaw 10 is then free to move in the direction of the jaw 2, and is carried in that direction 80 by the movement of the pin 8. As soon as the jaws close upon a nut or other object between them the pressure on the pin 8 is released, permitting the teeth 11 and 12 to 85 re-engage, as in said former invention. 90 When said teeth are in engagement the more force that is exerted to separate the jaws the more tightly the teeth engage, and resist such separation.

When it is desired to release the jaws from 95 engagement with a nut, the thumb of the operator is again engaged with the button 14, and a pressure exerted against the shoulder of the recess 17, sufficiently to turn the pin 8 slightly and release the teeth 11 and 12. 100 The pin 8 can then be moved outwardly again. As soon as the thumb is removed from the button the teeth are reengaged by the operation of the spring 13. It will be evident that by the pressure of the thumb 105 upon the thumb-button, as mentioned, the jaws 2 and 10 can be instantly closed or opened, as desired, and that the thumb-buttons on the ends of the pin are a sufficient distance from the jaws so that the same 110

can be readily manipulated, even when the jaws themselves are in close quarters.

The thumb-buttons on the opposite ends of the pin 8 are positioned with the recesses 5 projected in the same direction in each, so that when the tool is reversed, and the thumb of the left hand employed, the operation of the pin will be the same as when actuated by the right hand.

10 By having the recess 4 extend from one edge of the head to the other it is easy to assemble the parts of the wrench. It is found to be advisable to have the thumb-button on one end of the pin 8 formed solidly 15 thereon, the other thumb-button being perforated to receive the end of the pin after it has been united with the tongue 9, after which the end of the pin is upset against the button. It is essential that the inner faces 20 of said buttons shall move freely on the head of the wrench.

What I claim, and desire to secure by Letters Patent, is;

1. A wrench, comprising a recessed head 25 provided with a transverse slot, a jaw fixed on said head, a movable jaw having a tongue movable in said recess, said head and movable jaw having interengaging edges, means for holding said parts yieldably in engage-

ment, a pin movable in said slot and connected with said tongue, so as to impart a rocking movement thereto, and a thumb-button on the end of said pin, having a part engagable by the operator to give an initial rocking movement to said pin and disengage 35 the edges of said movable jaw and head.

2. A wrench, comprising a recessed head, provided with a transverse slot, a jaw fixed on said head, a jaw having a tongue movable in said recess, said head and last-named 40 jaw having interengaging edges, means for holding said head and movable jaw with their edges yieldably in engagement, a pin movable in said slot and having a pressed union with said tongue, so as to impart 45 movement thereto, both slidably and rockingly, and one or more thumb-buttons on the ends of said pin, having parts engagable by the thumb of the operator for moving the pin in one direction and other parts for 50 moving the same in the opposite direction, both of said parts being disposed so as to give an initial releasing movement to said movable jaw, to permit the free action 55 thereof.

In testimony whereof I affix my signature.

LOUIS R. CARBEIL.
